UNITED STATES PATENT OFFICE

2,548,623

BUFFING WHEEL

Carl F. Schlegel, Brighton, N. Y., assignor to The Schlegel Manufacturing Company, Rochester, N. Y., a corporation of New York

Application October 17, 1947, Serial No. 780,468

2 Claims. (Cl. 51—193)

1

This invention relates to a buffing wheel or polishing wheel and has for its principal object the provision of a generally improved and more satisfactory buffing or polishing wheel.

Another object of the invention is the provision of a buffing or polishing wheel of the type in which the working surface of the wheel is made up of strands or filaments extending radially of the wheel, in which the relation of the strands or filaments to each other is such as to give greatly improved results as compared with prior wheels having radial strands or filaments.

Another object is the provision of a wheel of the radial strand or filament type which is easy and inexpensive to manufacture and sturdy in use, and which has a relatively long life.

A further object of the invention is the provision of a buffing or polishing wheel of the radial strand or filament type, in which the strands or filaments are intertwined or interwoven with each other in such a manner that the wheel is considerably more rigid and has considerably more body or firmness than has been possible in previous radial strand wheels of the same size.

These and other desirable objects are accomplished by the construction disclosed as an illustrative embodiment of the invention in the following description and in the accompanying drawings forming a part hereof, in which:

Fig. 1 is a diagrammatic face view of a buffing wheel or polishing wheel in accordance with a preferred embodiment of the present invention;

Fig. 2 is a cross section taken centrally through the same;

Fig. 3 is an enlarged diagrammatic face view of the wheel shown in Figs. 1 and 2, illustrating the intertwining or weaving of the strands or filaments in greater detail;

Fig. 4 is a view similar to Fig. 3 showing an alternative form of weave;

Fig. 5 is a cross section taken substantially on the line 5—5 of Fig. 4;

Fig. 6 is a cross section taken substantially on the line 6—6 of Fig. 4;

Fig. 7 is a cross section taken substantially on the line 7—7 of Fig. 4, and

Fig. 8 is a cross section taken substantially on the line 8—8 of Fig. 4.

The same reference numerals throughout the several views indicate the same parts.

As a good illustration of the prior forms of buffing and polishing wheels of the radial strand type, reference is made to United States Patent 1,504,272 granted August 12, 1924, for an invention of Charles P. Schlegel. The construction

2

shown in said patent, although representing an advance over the constructions which had preceded it, has proven by experience to be not wholly satisfactory, partly because it has been difficult and expensive to weave, and partly because it has been a relatively soft and flexible weave which has resulted in a wheel which has been undesirably flabby and flexible unless built up to an undesirably great thickness and weight.

10 As contrasted with the weave shown in said prior patent, the construction disclosed in the present application can be manufactured or woven relatively easily and inexpensively, and results in a firm weave having more body or stiffness than the weave of said prior patent, whereby a buffing wheel or polishing wheel having a given stiffness can be made with a minimum number of layers of the fabric. The new weave here disclosed, in other words, has greater "body" or density and

15 greater stiffness than that shown in said prior patent, and also runs cooler than said prior weave, having less tendency to catch on fire during operation.

Referring now to the preferred form of construction as shown in Figs. 1, 2, and 3, the buffing wheel or polishing wheel comprises in general a fabric strip 11 of arcuate shape, wound upon itself with the different layers in overlying relation to each other in helical fashion, with as

20 many convolutions or turns as may be necessary to build up the required thickness of material. The outer arcuate edge 13 forms the working surface of the wheel, and is of any diameter desired. The inner arcuate edge of the strip is indicated at 15, and may, if desired, have the same radius as that of the arbor hole 17, but in order to economize on the amount of fabric material employed, it is usually advisable to make the radius of the inner edge 15 substantially

25 larger than the radius of the arbor hole 17, and to place a circular filler disk or block 19 of fiberboard, chipboard, or the like in the space inside the edge 15 of the fabric. In that event, the filler 19 is provided with the arbor hole 17 at its center.

30 A pair of thin disks 21 of canvas or the like lie on opposite faces of the filler block 19 and overlap the inner marginal edge of the fabric strip 11, as seen in Fig. 2, and are sewn to the filler block 19 and to the fabric strip 11 by spiral

35 stitching 23 or the like, which spiral stitching is continued outwardly beyond the disks 21 throughout most of the radial width of the fabric 11 (unless a relatively loose buff is desired) and serves to hold the different layers of the fabric 11 in cooperative relation to each other as

well as holding the fabric layers to the disks 21 and thereby holding them in cooperative relation to the filler block 19. If a loose buff is wanted, only a few of the innermost spiral convolutions of stitches 23 are used, the outer ones being omitted, so that the layers of fabric are stitched together only near their inner edges and are elsewhere not held tightly to each other.

As already stated, the body of the wheel is made up of one long arcuate strip of fabric, helically wound to provide any desired number of superimposed convolutions, three layers or convolutions being illustrated in Fig. 2 as a convenient example. The fabric strip 11 itself consists of weft strands or filaments extending radially, and a series of groups of warp strands which extend arcuately, concentric with each other and with the center of the finished wheel, the different groups of warp strands being spaced from each other in a radial direction. The number of groups of warp strands may be varied according to the diameter of the wheel and other factors. In the preferred construction shown in Figs. 1 and 3 as a typical example, five groups of warp strands are indicated, the innermost group of warp strands forming a selvage edge at the inner edge of the fabric being indicated in general by the numeral 31, the next group of warp strands spaced radially outwardly therefrom being indicated by the numeral 32, and the other groups of warp strands, successively outwardly in a radial direction, being indicated by the numerals 33, 34, and 35. In the practical weaving of the fabric, there is usually still another group of warp strands initially forming a selvage edge at the outer edge of the arcuate strip when it is initially woven, and then the weft strands are trimmed off or cut just inside of this outermost group of warp strands, so that this outer group of warp strands is not shown in the present drawings, which drawings are intended to illustrate the final wheel after the trimming operation takes place. In each group of warp strands, some of the strands go over certain weft strands while other warp strands go under those same weft strands, so that the warp strands are divided, as usual, into sheds through which the weft strands extend.

Through each single shed of the warp strands there are, in the preferred weave, a plurality of weft strands of various different lengths, some extending all the way from the outer edge to the inner edge of the wheel, others extending from the outer edge inwardly only as far as the warp strands 32, others coming only in as far as the warp strands 33, and others coming only as far as the warp strands 34. This is well illustrated in the enlarged diagrammatic view, Fig. 3. The space between the radial line *a* and the radial line *b* in Fig. 3 represents one shed through all of the different warp strands, while the space between the radial line *b* and the radial line *c* represents the next adjacent shed through all of the warp strands. The weft strands 41, 42, and 43, for example, are of full length (that is, they extend throughout the entire radial width of the strip of fabric) and are looped around the warp strands 31 to form a selvage edge, and then extend radially outwardly through the next shed to the left. Other full length weft strands 44, 45, and 46 also extend through the shed *a*—*b* and are looped around the weft strands 31 to form a selvage edge, thence extending outwardly through the next shed to the right (that is, the

shed *b*—*c*) being there designated by the numerals 51, 52, and 53.

These main radial weft strands 41 through 53, inclusive, although tightly compacted in the immediate vicinity of the inner warp strands 31 at the inner selvage edge of the material, will be progressively looser, of course, at points progressively farther outwardly toward the outer edge of the material, because of the arcuate shape of the material and the diverging nature of the radii of an arc, unless additional strands be introduced to take care of the greater length of the outer edge of the material as compared with the inner edge of the material. One way of introducing such additional strands is disclosed in said United States Patent 1,504,272, but, as already mentioned, this results in a rather flabby construction, not having the firmness and body which is desirable in a buffing wheel or polishing wheel of this kind. According to the present invention in its preferred form, the novel way of introducing the necessary additional strands is well indicated in Fig. 3 of the drawings, and this novel construction results, as previously stated, in a wheel having much greater firmness and body than the wheel shown in said prior patent. In the preferred form, each looped pair of shorter strands is embraced between a looped pair of longer strands, as indicated in Fig. 3. For example, the strands 61 and 62 constitute parts of a single strand extending from the outer edge of the material inwardly as far as the warp strands 34 and being looped around the warp strands 34 and then extending out to the outer edge again. The strand 61 lies in the shed *a*—*b* and the strand 62 lies in the shed *b*—*c*. These strands 61 and 62 are embraced tightly between the strands 63 and 64 which are similarly formed from a single continuous strand and extend inwardly from the outer edge as far as the warp strands 33, being looped around the strands 33 and then extending outwardly again to the outer edge, with the strand 63 in the shed *a*—*b* and the strand 64 in the shed *b*—*c*. These strands 63 and 64 are, in turn, embraced tightly between the strands 65 and 66 which similarly extend from the outer edge of the material to the warp strands 32 and are looped around the strands 32, the strand 65 lying in the shed *a*—*b* and the strand 66 lying in the shed *b*—*c*. These strands 65 and 66 are, in turn, tightly embraced between the full length strands 46 and 51, previously mentioned.

The same construction is used all the way along the curved length of the fabric material, at the junction between each two sheds, as is plainly seen from Fig. 3. The placing of the shorter strands in between the longer strands and in embraced relation thereto results in a construction which is particularly easy to manufacture, as well as having the other advantages already mentioned.

It is seen that in this construction the sheds are relatively large and contain a considerable number of weft strands, and also that each shed in each group of warp strands, except the innermost group 31, contains weft strands of various different lengths. In other words, each shed in the warp strand group 32 contains not only six of the full length weft strands, but also two of the next shorter weft strands which extend from the outer edge only to the warp 32 and which are looped around the warp strands 32. Likewise, each shed in the next warp group 33 contains six of the full length strands which go

all the way to the inner selvage edge, and two of the next shorter weft strands which go only to the warp strands 32, and two more of the next shorter warp strands which go only as far as the warp strands 33. Likewise the group 35 of warp strands (this being the outermost group of warp strands except for the outer selvage warp strands which are originally woven in the material and then later trimmed off) contains, in each shed, six of the full length weft strands, two of the next shorter weft strands which go only as far as the warp strands 32, and two of the next shorter weft strands which go only as far as the warp strands 33, and two of the still shorter weft strands which go only as far as the warp strands 34.

An alternative form of construction, shown in Figs. 4 to 8, inclusive, embodies the same general principle of embracing each pair of shorter weft strands between a pair of longer weft strands, although in this alternative construction the shed arrangement is quite different and the grouping of the pairs of weft strands is also quite different. From Figs. 4 to 8, which are essentially diagrammatic in character, it will be seen that the warp strands are arranged in various groups respectively designated by the numerals 101 (being the innermost group of warp strands, forming the inner selvage edge) 102, 103, 104, 105, 106, 107, and 108. There is, of course, in the initial manufacturing operation, still another group of warp strands forming the outer selvage edge, which are later trimmed off. The sheds in this construction are much smaller, each shed enclosing, for example, only two of the radial or weft strands. Some of the full length weft strands, coming all the way in to the innermost warp strands 101, are indicated individually for convenience by the numerals 111 to 124, inclusive. The weft strand 111, coming radially inwardly, is looped around the warp strands 101 at the inner selvage edge, and thence extends radially outwardly, forming the strand 112. Similarly the strands 113 and 114 are connected or looped to each other at their inner ends, and the strands 115 and 116 are likewise connected to each other at their inner ends where they are looped around the warp strands 101, and so on with the other weft strands. But in this instance, only the two weft strands 112 and 113 pass through one shed of the warp strands, while the next two weft strands 114 and 115 pass through the next shed of the warp strands, and the next two weft strands 116 and 117 pass through the next shed of the warp strands, and so on.

Some of the shorter weft strands are indicated individually by the numerals 130 and 135, inclusive. These weft strands 130 to 135 extend inwardly from the outer edge as far as the warp strands 104. As before, these shorter weft strands are looped around the warp strands at which they terminate, and then extend radially outwardly again, but with this difference from the previous construction, that the two strands which form one loop, instead of lying adjacent each other in adjacent sheds of the warp, are separated a considerable distance from each other and the loops jump over a number of intermediate weft strands as indicated at 136, 137, and 138. For example, the weft strand 131, after coming from the outer edge in as far as the warp strands 104, is looped at 136 across four of the longer weft strands 114, 115, 116, and 117, and then extends radially outwardly at 132,

alongside of another weft strand 133 of the same length, which similarly jumps at 137 over four of the weft strands 118 to 121, inclusive, and then extends radially outwardly at 134.

- 5 It may be said of this construction, just as of the construction previously described, that the shorter weft strands are arranged in pairs, each pair being embraced on both sides by longer weft strands, since the shorter weft strands 130 and 131 may be considered as one pair which are embraced by the longer weft strands 113 and 114, while the shorter weft strands 132 and 133 constitute another pair embraced by the longer weft strands 117 and 118. However, in 10 this instance, the two weft strands which constitute one pair are not the two strands which are looped with each other, whereas in the construction shown in Fig. 3 the two weft strands constituting one pair (65 and 66, for example) 15 are looped with each other at their inner ends. Similarly, the still shorter weft strands which do not extend even so far inwardly as the warp strand group 104, are arranged in approximately the same way. For example, some of the shorter 20 weft strands are indicated by the numerals 140 to 147, inclusive. These strands extend from the outer edge of the material in to the warp strand group 107, where they are looped around the warp strands in a manner to jump over several of the other weft strands, as shown. Thus the short weft strands 141 and 142 are connected to each other by the loop 148 which jumps over the full length strands 112 to 115, inclusive, and also jumps over the intermediate length strands 130 25 and 131. Likewise, the short weft strands 143 and 144 are connected to each other by the loop 149 which jumps over the full length strands 116 to 119, inclusive, and over the intermediate weft strands 132 and 133. As before, the strands 142 30 and 143 lying next to each other and extending through the same shed of the warp, may be considered as one pair, and it is seen that they are embraced on both sides by the longer strands 115 and 116. The short strands 144 and 145 likewise 35 constitute one pair, extending through the same shed of the warp, and are tightly embraced between the longer strands 119 and 120.

In either form of weave, whether it be that shown in Fig. 3 or that shown in Figs. 4 to 8, 40 inclusive, any desired number of different lengths of strands may be used, depending upon the radial width of the material and the tightness of weave desired. The construction shown in Fig. 3 uses radial weft strands of four different 45 lengths, and the construction shown in Fig. 4 uses radial weft strands of three different lengths, these being given merely as convenient examples. The use of a greater number of different groups of radially spaced warp strands, does not depart 50 from the principles of this invention.

The strands or filaments used in constructing the fabric may be of any desired kind, either metallic or non-metallic. For example, they may be of fine wires of copper or other suitable metal, 55 or artificial fibers such as rayon or nylon, or natural fibers of either animal or vegetable origin, such as wool, linen, or cotton. In most cases it is preferred to use strands of cotton, either in the form of individual threads, or preferably in 60 the form of tightly twisted cables or cords as indicated in Figs. 3 and 5, each cable being made up usually of three smaller cords twisted together. It is also preferred in many cases that these 65 cables used in forming the weft strands be impregnated with a suitable adhesive, preferably 70

latex, to tend to hold the individual fibers of the cable more firmly and stiffly in place, thus producing a more firm buffing wheel or polishing wheel. When the weft is made up of cables each constituting a plurality of cords twisted together, the body of the wheel is relatively firm and yet the outer ends of the cables will ravel somewhat as indicated diagrammatically in the drawings, resulting in a soft outer working face of the wheel, which is highly desirable.

It will be obvious to those skilled in the art that the fabric construction here disclosed may be woven on a loom, or may be formed on a knitting machine.

Comparing the two constructions here disclosed with each other and with the construction shown in said United States Patent 1,504,272, it may be said that in both of the present constructions, each pair of two adjacent weft strands of shorter length is tightly embraced on both sides by weft strands of longer length. For example, in the construction shown in Fig. 3, the shorter length weft strands 61 and 62 are embraced by the longer weft strands 63 and 64, and these strands in turn are embraced by the still longer weft strands 65 and 66, and so on. In the other construction shown in Fig. 4, the shorter weft strands 142 and 143 are embraced by the longer weft strands 145 and 146, while the weft strands 132 and 133 are embraced by the longer weft strands 117 and 118. This characteristic is not true, however, of the construction shown in said United States Patent 1,504,272, for in that patent the pair of shorter weft strands *b* lies between the longer weft strands *a* on one side, and the still shorter weft strands *c* on the other side, and this same relationship of being adjacent a longer strand on one side and a shorter strand on the other side is true of all of the pairs of weft strands *b* to *f*, inclusive, in said patented construction.

Another characteristic of the present constructions which is not found in said prior patent, is that each pair of longer weft strands connected to each other by a loop at their inner ends, has its strands separated from each other throughout at least a part of their length by interposed weft strands of a shorter length. For example, in Fig. 3, the looped pair of strands 46 and 51, as well as the looped pair 45 and 52, and the looped pair 44 and 53, each have one member of the pair separated from the other member of the pair by the interposed shorter strands 65 and 66, and the strands 65 and 66, constituting a single looped pair, are separated from each other by the shorter strands 63 and 64. In the other construction, shown in Fig. 4, the strands 117 and 118, for example, constituting one looped pair, are separated from each other by the shorter strands 132 and 133. Also the strands 131 and 132, which are looped together, are separated from each other through part of their length by the interposed shorter strands 142 and 143. This relationship is not true of said prior patent, however, in which each looped pair of strands does not have its members separated from each other by any interposed strands.

Still another characteristic by which the preferred construction shown in Figs. 1-3 of the present drawings differs from the construction in said prior patent, is that in the present construction of Figs. 1-3, there are the same number of sheds in all of the different groups of warp strands, and the corresponding sheds in all the different groups of warp strands 31, 32, 33, etc.,

all open and close at the same time in the manufacturing operation. The difference in circumferential length of the material at different radial distances from the center, is achieved in the preferred construction by varying the number of weft strands at different radially-spaced parts of the shed, rather than by varying the number of sheds at different radially-spaced parts of the material as was done in said prior patent. This preferred construction can be woven much more quickly and economically than a construction such as shown in said prior patent, wherein a greater number of sheds are used in the warp strands near the outer perimeter of the buff than in the warp strands closer to the center of the buff.

In the modified construction shown in Figs. 4-8 of the present drawings, a greater number of sheds are used in the warp strands near the outer edge of the buff, than in those closer to the center, and in this respect the construction is similar to that shown in said prior patent, but in other respects the weave is quite different as already explained, and the construction of Figs. 4-8 of the present invention can be woven more quickly and economically than that of said prior patent, even though the number of sheds is not the same in all the different groups of warp strands.

It is features or characteristics such as these, which are believed to give the present construction its superiority over the construction disclosed in said United States Patent 1,504,272, and which result in the construction of the present invention being more firm and tight and having more "body" for a given size and weight of wheel, because the weft strands in the present instance are more intimately intertwined and associated with each other than was possible with said prior constructions.

Another advantage of the present constructions over said prior patent is that the present constructions are more easily and more quickly woven, and require less material, than the patented construction. Also the present constructions run cooler in actual use than the patented construction, this being probably due to a fan action induced by the particular weaves herein disclosed. Also the present constructions, because of increased density as compared with the patented construction, have better wearing qualities and better cutting qualities, and hold more abrasive so that less pressure by the operator is required.

As used in the accompanying claims, the words "buff" and "buffing wheel" are intended to be interpreted in a broad sense as including a polishing wheel.

It is seen from the foregoing disclosure that the above mentioned objects of the invention are admirably fulfilled. It is to be understood that the foregoing disclosure is given by way of illustrative examples only, rather than by way of limitation, and that without departing from the invention, the details may be varied within the scope of the appended claims.

What is claimed is:

1. A buffing wheel having a body formed of a plurality of superimposed layers of fabric material of arcuate shape with substantially concentric arcuate warp strands and with substantially radial weft strands of a series of different lengths, each weft strand of a length shorter than the longest lying in juxtaposition to another weft strand of the same length on one

side and a weft strand of a longer length on the other side.

2. A buffing wheel having a fabric body formed of a plurality of helically wound convolutions of an arcuately woven strip of textile fabric, said strip having a series of radially spaced groups of arcuately extending warp strands having weaving sheds, and a multiplicity of radially extending weft strands with at least two weft strands extending through each shed of the innermost group of warp strands and a progressively greater number of weft strands extending through each shed of each group of warp strands located progressively farther outwardly from said innermost group, one complete circle of said woven

10

strip having in each group of warp strands the same number of sheds as in every other group of warp strands.

CARL F. SCHLEGEL.
